Primary Examiner — David Muller

(74) Attorney, Agent, or Firm — Finnegan, Henderson,
Farabow, Garrett & Dunner LLP(57) **CLAIM**The ornamental design for an enfit connector, as shown and
described.**DESCRIPTION**

FIG. 1 is a top front right perspective view of a first embodiment of an enfit connector showing our new design;
FIG. 2 is a top rear left perspective view thereof;
FIG. 3 is a top plan view thereof;
FIG. 4 is a bottom plan view thereof;
FIG. 5 is a left side elevation view thereof;
FIG. 6 is a right side view thereof;
FIG. 7 is a rear elevation view thereof; and,
FIG. 8 is a front elevation view thereof.

The broken lines of even length shown in the drawings
illustrate portions of the enfit connector that form no part of
the claimed design.
